W. L. LAWRENCE

SHOE HEEL

Filed Oct. 9, 1923

INVENTOR
W.L. Lawrence

BY
Z. Ledermann
ATTORNEY

UNITED STATES PATENT OFFICE.

WILLIAM L. LAWRENCE, OF BROOKLYN, NEW YORK.

SHOE HEEL.

Application filed October 9, 1923. Serial No. 667,442.

To all whom it may concern:

Be it known that I, WILLIAM L. LAWRENCE, a citizen of the United States, residing at Brooklyn, in the county of Kings and State of New York, have invented certain new and useful Improvements in Shoe Heels, of which the following is a specification.

The main object of this invention is to provide a shoe heel composed of two parts, a main body and an auxiliary part which may be readily attached in place after the original portion has been removed from the main body.

Another object is to provide a shoe heel, the rear corner of which has an inclined surface upon which a second member may be attached after the original has been worn down.

These and other objects will become apparent in the description below, in which characters of reference refer to like-named parts of the drawing.

Referring briefly to the drawing, Figure 1 is a perspective view of a shoe inverted in order to show my invention.

Figure 2 is a sectional elevational view thru the shoe heel.

Figure 3 is a perspective view of the main body of the shoe heel with the rear portion detached.

Figure 4 is a perspective view showing the rear portion of the heel with the attaching lugs thereon.

Referring in detail to the drawing, the numeral 10 indicates the sole of a shoe at the rear end of which a heel 11 is mounted. The heel on the usual shoe is generally topped with a rubber body 12 which has a flange 13 on its under side, said flange fitting snugly into a smaller recess formed within the body 11 of the heel. This type of rubber heel does not require nails for securing the rubber body 12 in place, as the flange 13 serves to retain said body in place upon the heel 11. The rear portion of a rubber heel is worn down much more quickly than the remainder of the same, and for this reason I provide my heel with an inclined surface 15 at its rear end. Projecting downwardly from this surface, holes of square or any other shape desired, are provided and are indicated by the numeral 16. The lower portions of the openings are provided with enlarged pockets 17, the purpose of which

will be more fully hereinafter described. An additional heel portion, substantially triangular in cross section and having an inclined face 17, is mounted on the surface 15, and when in mounted position, tops the cut-away portion of the heel body 12 and forms a rectangular body therewith. A pair of lugs 18 of similar shape as the openings 16, project upwardly from the inclined surface 17 and have enlarged heads 19.

As previously stated, the heel wears down more quickly at the rear end, and for this reason my heel is particularly adaptable. The main body of my heel is preferably molded in the shape shown in Figure 3 with the inclined surface 15 and the openings communicating with the inclined face thereon. The additional portion of the heel 20 is designed to be mounted upon the body 12 when the latter has had its previous and similar member worn completely off. In order to mount member 20 upon the body 12, the surfaces 15 and 17 are treated with a rubber cement or similar compound, and the lugs 18 are inserted into their respective openings 16. In urging the heads 19 of said lugs into the openings, the heads will be slightly compressed until they arrive at the pocket 16, when they will again assume their normal position therein. It may be readily seen that one of the advantages of this type of heel is that said heel may be repaired while the shoe is on the foot and no skill is required by the repairer, as the only operation required is to cover the adjacent surfaces of members 12 and 15 with a cement substance and then urge the lugs into their openings. By treading on the heel after this operation has been completed, member 20 will assume its correct position on body 12 and no additional care is required.

I claim:

A heel comprising a rubber body, means for securing the rubber body to the shoe, an inclined surface at the rear of said heel, the cut-out portion bounded by the inclined and tread surface of the heel body being substantially triangular in cross section, said heel having openings communicating with the inclined surfaces the openings being rectangular in outline, the openings having pockets formed at their lower ends, an additional heel member substantially triangular in cross section, one of the surfaces of the

additional member being adapted to lie on the inclined surface of the heel body, lugs integral with the additional member projecting from one surface of said additional member, the lugs being engageable in the openings of the heel body, heads on said lugs, the latter being adapted to be retained

in said pockets, said heads retaining the additional heel member securely upon the inclined surface of the heel body the additional heel member being removable by removing the lugs from the openings. 10

In testimony whereof I affix my signature.

WILLIAM L. LAWRENCE.
